United States Patent Office

Des. 203,761
Patented Feb. 15, 1966

203,761

FOOD MIXER OR THE LIKE

George H. Frost, Ashland, Ohio, assignor to Sunbeam Corporation, Chicago, Ill., a corporation of Illinois

Filed June 16, 1965, Ser. No. 85,766

Term of patent 14 years

(Cl. D44—1)

Fig. 1.

Fig. 2.

Fig. 3.

FIG. 1 is a perspective view of a food mixer or the like embodying my new design;

FIGS. 2 and 3 are top and bottom plan views, respectively thereof; and

FIGS. 4, 5 and 6 are side, front and rear elevational views, respectively, thereof.

I claim:

The ornamental design for a food mixer or the like, as shown.
